INVENTOR.

Charles H. Brower
BY Cyrus N. Anderson

ATTORNEY.

UNITED STATES PATENT OFFICE.

CHARLES H. BROWER, OF PHILADELPHIA, PENNSYLVANIA.

TRUCK.

Application filed September 27, 1921. Serial No. 503,542.

To all whom it may concern:

Be it known that I, CHARLES H. BROWER, a citizen of the United States, and a resident of Philadelphia, in the county of Philadelphia and State of Pennsylvania, have invented an Improvement in Trucks, of which the following is a specification.

My invention relates to trucks which are adapted for use in the collection of soiled dishes, napkins, etc., in cafeterias, restaurants and the like, and it has for its object to provide a device of this character having means adapted to receive and hold in separate compartments or containers the dishes of different sizes and shapes and also to provide means for disposing of particles of uneaten food ordinarily and commonly denominated "slop."

A further object of the invention is to provide a construction of the character described in which the different compartments are conveniently arranged with relation to each other and so that full use thereof may be made at a minimum of inconvenience; and a still further object is to simplify the construction so that it may be manufactured at a minimum cost whereby its use may become more general.

Other objects and advantages of the invention will be pointed out in the detailed description thereof which follows or will be apparent from such description.

In order that the invention may be readily understood and its practical advantages fully appreciated reference may be had to the accompanying drawings in which I have illustrated one form of mechanical embodiment thereof. However, it will be understood that changes in the details of construction may be made within the scope of the claims without departing from the invention.

In the drawings:

Fig. 1 is a perspective view of a truck embodying my invention;

Fig. 2 is a top plan view of the same;

Fig. 3 is a vertical longitudinal section taken on the line 3—3 of Fig. 2;

Fig. 4 is a similar view taken on the line 4—4 of Fig. 2;

Fig. 5 is a transverse sectional view taken on the line 5—5 of Fig. 1;

Fig. 6 is a horizontal sectional view taken on the line 6—6 of Figs. 3 and 4; and

Fig. 7 is a perspective view showing a portion of the structure removed or detached from the remaining portion thereof.

Referring to the drawings, it will be noted that the structure includes a frame portion comprising angle irons 1 upon and around which the remaining portion of the structure is constructed.

The truck comprises a compartment 2 access to which is provided through openings 3 and 4 in the front and rear walls 5 and 6. These openings do not extend all the way to the bottom 7 of the structure so that lower portions of the side and rear walls serve to retain within the compartment 2 such articles as may be placed therein. This compartment may be employed for trays or for the larger dishes if desired. A second compartment 10 is provided directly above the compartment 2, the lower rear portion of which is permanently closed by an upwardly extending portion 11 of the rear wall 6. The lower front portion of said compartment 10 is adapted to be closed by means of a drop door 12 hinged to the upper portion of the front wall 5. When open the door 12 is held in horizontal position by means of the chains 13, the outer ends of which are secured to the outer edge portions of the door while the inner ends thereof are secured to the upper edge portions of extensions of the front wall 5. The door 12 is adapted to be retained in closed position by means of the catches 14 which are adapted to be turned into engagement with the inner sides of the forward legs of the inverted U-shaped members 15 which are secured at their lower ends to the plate 17 constituting the top of the compartment 2 and the bottom of the compartment 10. The compartment 10 is adapted to receive the larger dishes, such as plates, saucers and the like.

Situated above the compartment 10 is a box or container 20 which is divided by a partition 21 into two compartments 22 and 23. The box 20 is supported upon the upper horizontal portions of the inverted U-shaped members 15. These compartments 22 and 23 are adapted to receive smaller dishes, such as cups and glasses.

At one end of the structure and between portions of the front and rear walls 5 and 6 compartments or receptacles are provided for different purposes. 25 designates a receptacle or chamber which is adapted to contain clean water for the moistening of cloths or the like for use in wiping or cleaning off the tables. The water is adapted to be discharged from the receptacle 25 through a

spigot 26. At the opposite side of the structure; that is, in rear of the receptacle 25, a funnel-shaped opening 30 is provided through which the "slop" may be delivered 5 into a bucket 31 situated in a chamber 32 underneath the lower end of the funnel 30. The bucket 31 may be inserted into and removed from the chamber 32 through an opening 33 which is adapted to be opened and closed 10 by a hinged door 34. A receptacle or chamber 35 is provided for soiled napkins and the like. The top of this receptacle is open as indicated in the drawings, so that the soiled napkins and the like may be readily thrown 15 or placed therein. They are adapted to be removed through an opening 37 in the side of the receptacle which is adapted to be closed by means of a door 38. This door as well as the door 34 is adapted to be fastened 20 when closed by means of the usual catches which are adapted to be turned into open and closed position by turn buttons 39.

At its opposite end the structure is provided with a recess formed by the extensions 25 of the front and rear walls and the end wall 40 of the compartment 10 within which recess the box 41 is adapted to be seated. This box is divided by the partitions 42 into a plurality of compartments 43. The upper 30 end portion of the outer side of the box 41 is inclined outwardly as indicated at 44. In order to more securely retain the box 41 in position within the said recess hooks 45 are provided upon the upper edge of the inner side thereof which hooks are adapted to engage the top edge of the end wall 40 of the compartment 10. A receptacle or compartment 50 is provided for receiving and holding broken china. An opening 51 is provided in the outer side of this receptacle, which opening is adapted to be closed by a door 52. The said door is adapted to be held in closed position by a catch 53.

In order that the truck may be readily 45 moved from place to place I have provided wheels 55 upon which the same is supported, and I have also provided a handle 56 to further facilitate the moving of the truck from place to place. In the use of the device 50 such dishes as may have thereon or therein uneaten portions of food, whether solid or liquid, may be brought down or struck down upon a resilient buffer 57 situated adjacent the top of the funnel opening 30 to remove 55 therefrom the uneaten portions of food and to cause the same to pass through the funnel opening 30.

It will be seen that I have provided a compact structure provided with a plurality of 60 compartments and receptacles adapted to the purposes for which they are designed as above set forth.

I have found from actual experience that 65 by the use of a device of this character the labor of collecting used, soiled dishes and

conveying them to some central point to be washed is greatly reduced. I have also found from actual experience that considerable time may be saved by the use of a truck embodying my invention over what would be required if the dishes were collected upon waiters and carried by hand to such central position or station to be washed or cleansed. 70

Having thus described my invention, what I claim and desire to secure by Letters Patent is: 75

1. A truck of the character described, comprising a plurality of compartments located one above the other, the said compartments being adapted to receive and hold dishes of different sizes, a plurality of receptacles supported upon the said truck but detachable therefrom, said receptacles being adapted to receive and hold small articles such as knives, forks, spoons and the like, a receptacle for receiving soiled napkins, a receptacle for receiving broken china, and a receptacle into which slop is adapted to be discharged through an opening in the truck structure, and a buffer associated with the entrance into said last mentioned receptacle, substantially as described. 80

2. A truck adapted to the collection of soiled dishes, napkins and the like, comprising a body portion including a plurality of centrally disposed compartments arranged one above the other, the said compartments being adapted to receive and hold dishes of different sizes, a receptacle divided into a plurality of compartments, the said receptacle having hooks by means of which it may be attached to an end wall of one of the said compartments, and the said body also including beyond the opposite ends of said first named compartments a plurality of receptacles, one of which is adapted to receive soiled napkins, the other one of which is adapted to receive uneaten portions of food, and the other one of which is adapted to receive and hold water, and a buffer associated with the second of the last named receptacles, substantially as and for the purpose described. 100

3. A truck for collecting soiled dishes and other dining-room utensils, comprising a body including two centrally disposed relatively large compartments one above the other and a box situated above the top compartment, said box being divided into a plurality of compartments, a box detachably connected with one end portion of the said body, said last named box being divided into a plurality of relatively small narrow compartments the upper end portions of the outer wall of which are inclined outwardly, and the said body also including at its opposite end a receptacle adapted to receive soiled napkins, a funnel-shaped opening through which uneaten portions of food are adapted to be delivered into a receptacle for 110 115 120 125 130

- receiving the same, and a receptacle for holding water, said receptacle being provided with a spigot for the discharge of water therefrom, substantially as described.
5. 4. A truck comprising a body including a compartment in the lower portion thereof, a top for said compartment, supporting members secured to said top and extending upwardly therefrom, a box supported upon 10 said members the bottom of which constitutes a top for a second compartment situated above the first named compartment, an upwardly extended portion of the rear wall of the body of said truck partially closing 15 the rear side of said second named compartment and the opposite front side of said compartment being adapted to be opened and closed by a drop door, and the top of the
- first named compartment and the opposite side walls of the said body being extended to 20 form a recess, a box secured in said recess between the oppositely disposed extended portions of the said walls, the upper portion of the outer wall of said box being inclined outwardly, and a receptacle adjacent said 25 box for receiving and holding broken crockery, and the opposite end portion of the said body being extended beyond the said compartments and being provided with receptacles of the character and for the purpose 30 described.

In testimony that I claim the foregoing as my invention I have hereunto signed my name this 24th day of September, 1921.

CHARLES H. BROWER.
